Long. Black and Allstatter.
Mower.

No 19703

Patented Mar. 23, 1858.

UNITED STATES PATENT OFFICE.

J. M. LONG, P. BLACK, AND R. ALLSTATTER, OF HAMILTON, OHIO.

IMPROVEMENT IN HARVESTERS.

Specification forming part of Letters Patent No. 19,703, dated March 23, 1858.

To all whom it may concern:

Be it known that we, JOHN M. LONG, PETER BLACK, and ROBERT ALLSTATTER, of Hamilton, in the county of Butler and State of Ohio, have invented a new and useful Improvement in Harvesters; and we do hereby declare that the following is a full, clear, and exact description of the construction and operation of the same, reference being had to the annexed drawings, forming part of this specification, in which—

Figure 1 is an elevation of gear side of machine. Fig. 2 is a rear elevation of the machine. Fig. 3 is an elevation of divider side. Fig. 4 is a section on xx through axis of gear-wheel, showing manner of attaching axle to frame.

Similar characters of reference in the several figures denote the same part.

Our invention has reference to the manner of elevating the cutter-bar and of supporting the platform.

The details of construction and operation will readily be understood from the following description and reference to the drawings:

The machine is supported by wheels $W W'$, the axle a of the former being secured to the box b , movable in the curved slot c of a guide-piece, d , secured to the gear-support A of the main frame. The box b is secured to the guide-piece d by a nut, e , on the end of axle a . This box has an arm, f , extending forward and connected with a bar, g , running across the piece A of frame by an eye, as shown in Fig. 1. The lever l , secured to the box, serves to move the box in its guides d when nut e is loosened, the frame of the machine adjusting itself to the desired height. The axle a' of wheel W' moves in guides d' , and is held in position by a nut, e' . The axle passes through a lever, l' , having its fulcrum at h on upright i . By this construction the divider side of the machine is adjusted to the elevation given the opposite side.

The driver's seat B is upon a tongue, C , hinged to the main frame at k , and supported upon wheels D to the axle, of which the draft-pole is secured. The gear-support A runs up toward the rear, as shown in Fig. 1, for the purpose of permitting the cut grain to be more

readily removed from the platform and deposited upon the ground. At its upper extremity it is connected by the bar E with the inclined brace F on the opposite side of the machine.

Running through the extremities of the bar E and curving under it, is the stay-rod G , supporting the rear of platform P by the suspending-rods $r r$, as shown in Fig. 2, the platform being attached by the points of braces t entering between the plates of the finger-bar and the suspension-rods aforesaid.

The inclined portion A of the frame has a lever, L , reaching to the driver's seat. This lever is jointed to a lever, L' , attached to tongue C . The connection of the two levers $L L'$ is directly over joint K , by which the tongue is connected with the main frame, so that the hand of the driver upon the extremity of lever L will cause this joint to rise or fall, and thus regulate the elevation and depression of the finger-bar, the jointed levers, with the tongue and frame A , acting upon the principle of the toggle joint.

The elevation of the cutter-bar is adjusted by means of the guide-pieces in which the axles of the wheels move, as hereinbefore described, and any temporary elevation of the finger-bar for the passage of obstacles or other purpose is given by the hand of the driver acting on lever L .

The inclination of the piece A of the frame permits the discharge of the cut grain from the end of the platform without an inconvenient increase of space between the frame and platform. The stay-rod G gives great stiffness to the bar E above it, and prevents it from sinking when the weight of the platform and raker comes upon it. The rod passes through two eyes, $m m$, at the extremities of depending staples in the under side of the bar. The pressure of the rod is transmitted through these staples when it is drawn tight by the nut at its extremity. There is thus formed a compound brace-piece and suspending-bar.

What we claim as our invention, and desire to secure by Letters Patent, is—

1. The combination of lever-box b , guide-piece d , and short axle a , with nut and screw,

constructed, arranged, and operated substantially as and for the purposes set forth.

2. The stay-rod G, in combination with the bar E, substantially as and for the purposes set forth.

3. Supporting the rear of the platform by suspension from the stay-rod, substantially as and for the purposes described.

In testimony whereof we have hereunto

signed our names before two subscribing witnesses.

JOHN M. LONG.
PETER BLACK.
ROBERT ALLSTATTER.
